UNITED STATES PATENT OFFICE.

HENRY L. BONNEY, OF NORTH ANDOVER, MASSACHUSETTS, ASSIGNEE OF ONE-HALF
TO GEORGE GIBSON BROWN, OF LAWRENCE, MASSACHUSETTS.

SELF-THREADING SHUTTLE.

Application filed November 6, 1923. Serial No. 673,083.

To all whom it may concern:

Be it known that I, HENRY L. BONNEY, a citizen of the United States, a resident of North Andover, in the county of Essex and 5 State of Massachusetts, have invented an Improvement in Self-Threading Shuttles, of which the following is a specification.

This invention relates to that class of shuttles employed in automatic looms which 10 are threaded automatically when the bobbin is inserted, the threading action being partly performed on the first pick and finished on the second.

In shuttles of this character, it is not 15 only necessary that on the first pick the thread shall be drawn into the threading slot into such a position that the threading operation will be completed on the second pick, but it is also usually necessary to provide means to retain the thread in the 20 threading slot in such a position, during the time in which the shuttle is in the shuttle box between the first and second pick, that the operation will be completed.

25 Unthreading at the end of the first pick, or beginning of the second, is principally due to the kinking of hard twisted thread when it becomes slack at the end of the flight of the shuttle, and in case it should 30 pass back around the thread retaining means, the shuttle will become completely unthreaded as it passes from the shuttle box, at the beginning of the second pick.

One of the objects of my invention is to 35 provide an automatically threading shuttle in which the drawing of the thread into the threading slot past the thread retaining beak, which is usually employed, will be insured by the straight pull on the thread 40 due to the action of the first pick, and in which the possibility of unthreading by the kinking or thrashing about of the thread, after it has been drawn past the beak at the end of the first pick, will be obviated.

45 In shuttles of this character, it has been the usual practice to locate the tension device in the throat of the shuttle, or at the point where the thread leaves the bobbin chamber, the most common form of tension 50 device in use being a piece of felt over which the thread is drawn. An objection to this arrangement is that the thread is likely to "balloon" or swing about the center line of the bobbin as an axis, as it is drawn 55 from the bobbin and as a result the tension

action of the felt, when located in the position above described, is variable, or too great at sometimes and too small at others.

A further object of my invention is to provide a tension device which is so located 60 and arranged that its action will not be affected by the "ballooning" of the thread, so that a practically constant tension will be maintained on the thread at all times, and in this connection, another object of 65 the invention is to provide an improved means or manner of securing the tensioning means in position, so that the expense of manufacture may be reduced.

I accomplish these objects by means of 70 the construction hereinafter described and shown in the accompanying drawings, in which:

Fig. 1 is a top plan view of the thread delivery end portion of a self threading 75 shuttle embodying my invention.

Fig. 2 is a central longitudinal vertical section thereof on line *a*—*a* of Fig. 1.

Fig. 3 is a horizontal section on line *b*—*b* 80 of Fig. 2.

Fig. 4 is a similar view at line *c*—*c* of Fig. 2.

Fig. 5 is a perspective view of the thread delivery end of the shuttle.

Figs. 6 and 7 are, respectively a side 85 elevation, partly in section, and a bottom plan view of the threading block.

As shown in the drawing, the shuttle body 2 is provided with a cylindrical throat or passage which is in central longitudinal 90 alignment with the longitudinal center line of the bobbin 3, said passage being flared at its outer end. The wood of the shuttle has a longitudinal slot 4 which leads to said passage, the sides of the slot being oppositely beveled at their upper ends to form inclined faces 5 and 6 to guide the thread into the slot as it is drawn forwardly. The wood of the shuttle is also recessed from 95 its upper side to receive the metal threading block, which comprises a somewhat circularly shaped shank 7, having an outwardly flaring or inverted trunco-conical shaped head portion 8 from one side of which the beak 9 projects horizontally the 100 edges 10 and 11 of said beak being tangentially arranged with relation to the circular upper edge of the head portion and converging to its end. The edge 10 of the beak 105 extends approximately parallel to, but in 110

slight divergence with the middle longitudinal line of the shuttle, and the edge 11 extends transversely of the shuttle in an oblique direction to the rear side of the slot 12 in the shuttle, which leads to the shuttle eye. The sides of said eye are protected by cylindrical thread guide posts 13 and 14. The end-portion of the beak is provided with a depending thread-retaining lip 15, the outer side of which is continuous with the edge 10, and with a thread-retaining horn 16, the outer side of which is continuous with the edge 11. The lip 15 depends to its greatest extent at the extreme end of the beak and the horn 16 depends into a recess 17 formed in the shuttle wood to prevent unthreading. The portion of the edge of the head 8, immediately adjacent the edge 10 of the horn, extends obliquely across the longitudinal slot 4, so that edge 10 is disposed at the outer side of the line of the slot 4, and may diverge slightly therefrom, as shown, the horn thus extending somewhat laterally of the slot. The side wall of the threader block chamber is provided with a recess 18 to receive said laterally projecting portion, the bottom of which is parallel to the edge 10, said recess terminating in an oblique shoulder 19, which extends inwardly past the tip of the beak towards the tip of the shuttle at a sufficient distance from the tip of the beak to provide a clear passage for the thread therebetween. The tip portion of the shuttle is provided with a longitudinal groove 20 arranged in position to receive the thread when it is drawn longitudinally of the shuttle at the end of the first pick, said groove opening to the threader block chamber somewhat below the level of the under side of the horn, the side 20' being extended vertically above the upper side of the horn and being disposed in a plane which intersects the edge 11 of the beak at a short, but substantial distance from the tip thereof.

With the above described arrangement when the thread is drawn longitudinally of the shuttle on the first pick, one or the other of the oppositely inclined faces 5 and 6 will deflect the thread into the entrance to the threading slot, then it will be deflected by the edge of the beak, or the wood of the shuttle at the opposite side of the slot from the beak, into the front portion of the slot, so that it will be drawn down past the retaining lip 15 and beneath the horn, and will be drawn approximately straight from the throat of the shuttle through the groove 20, the arrangement being such that practically no obstruction will be presented to this part of the threading action, the slight deflection caused by the threading block at the point where the edge 10 of the beak meets the head in no way interfering with the threading action.

When the thread becomes slack, on entering the shuttle box at the end of the first pick, and, by kinking or otherwise, tends to thrash back into the front end of the slot between the lip of the beak and the adjacent wood of the shuttle, or the shoulder 19, the face formed by the side 20' of the groove 20 will act as a guard to deflect the thread away from the entrance to the slot, so that it will be caught by the edge 11 of the beak and prevented from being drawn into said slot entrance. As the edge 11 of the beak extends obliquely from the tip of the beak, away from the adjacent end of the shuttle, it tends to deflect the thread towards the shuttle eye, so that, on the next pick, the threading operation will be completed, and the tendency to unthread at the middle of the threading operation will be obviated.

The shank 7 of the threader block forms the inner side of the thread passage at the point at which the passage extends transversely to the shuttle eye, the lower end of the shank resting firmly on the bottom of the chamber which receives it, and said block being securely clamped in position by the cross bolt 22, or other suitable means. The side portion of the shank about which the thread is drawn at approximately right angles, as it is drawn from the longitudinal portion of the thread passage to the eye, is recessed from its lower end to a point above that normally engaged by the thread and a hole is bored upwardly in the shank from the upper end of the recess to form a socket in which a thread guide post 21 is mounted, said post extending to the bottom of the shank so that its lower end engages the bottom of the chamber, and being arranged so that the thread is drawn tangentially about the same or is engaged therewith for about one-fourth its circumference, as the direction in which it is drawn is changed from longitudinal to transverse.

The recess in the shank 7 in which the post 21 is located is of segmental form, so that the width of the space from the post to the side of the recess is uniform, said recess thus opening at each side of the post. This space is completely filled with a tension felt 23, which is secured in position thereon, the ends of the felt being arranged to extend beyond the sides of the shank at each side of the post 21, and into the line in which the thread is drawn, as it is drawn about said post, so that the thread will be drawn into the felt at each side of the post, as shown in Fig. 4, as it is drawn from the bobbin to the eye. The felt 23 will thus act as a drag on the thread at two points, and as the thread must be drawn sharply against the post 21, it must necessarily be drawn against both end portions of the felt at all

times, so that a suitable drag or tension will be constantly placed on the thread, which will in no way be affected by the "ballooning" or thrashing of the thread. When the threader block is in position, the felt 23 will be securely held against displacement, but when it becomes necessary to renew the felt, this may be readily done by removing the block, picking out the old piece and pushing a new piece into the recess behind the post 21, the latter thus serving as a retaining means for the felt, as well as a thread guide. In practice the post 21 will be of porcelain if the shuttle is used for worsted and of metal if it is used for cotton.

The above described construction is less expensive to manufacture than many shuttles of this general type, as the threader block is a simple casting and the chamber 20 which receives it may be largely made by boring.

I claim:

1. A self-threading shuttle having a slotted side-delivery eye and a thread passage 25 leading longitudinally from the bobbin chamber and transversely to said eye, a threading block disposed in the rear of the transverse portion of the passage and comprising an upright shank having a horizontally projecting beak at its upper end, a thread guide post mounted in the lower end of said shank at the vertex of the angle between said passage portions to cause the thread to be drawn against said post as it is drawn to said eye, said shank being recessed in the rear of the thread engaged portion of the post and having thread tensioning material inserted therein and extending into the line of the thread as it is drawn about the post to engage the thread before and after it is drawn past the same and cause a drag on thereon at each point of engagement.

2. A self-threading shuttle having a side-delivery eye and a thread passage extending longitudinally thereof from the bobbin chamber and transversely to said eye, a threading block having a vertically disposed shank mounted in the shuttle in the rear of the transverse portion of said passage and having a socket extending upwardly therein from its lower end, a thread guide post mounted in said socket at the vertex of the angle of said passage in position to cause the thread to be drawn against the same as it is drawn from the eye, said post ex-

tending to the lower end of said shank and said shank being recessed in the rear of the lower portion of said post and having a tension felt held in said recess by said post 60 and arranged to project at each side thereof in position to cause the thread to be drawn against each projecting portion of the felt, as it is drawn against the post.

3. A self-threading shuttle having a side-delivery eye and a thread passage leading longitudinally from the bobbin chamber and transversely to said eye, a threading block mounted in the shuttle in the rear of the transverse portion of said passage, a 70 vertical thread-guide post mounted at its upper end in said block and depending to the bottom of said passage at the vertex of the angle therein in position to cause the thread to be drawn thereagainst as it is 75 drawn to the shuttle eye, said block being recessed in the rear of the thread guiding portion of said post and having a tension felt held therein in position to project at each side of the post into engagement with 80 the thread as it is drawn against the post in its passage to the eye.

4. A self-threading shuttle having a side-delivery eye, a threader block chamber and a thread passage leading longitudinally 85 thereto and transversely therefrom to said eye, a threader block comprising an upright shank having a horizontally projecting beak and means for securing the same in said chamber with the lower end of its 90 shank engaged with the bottom thereof, said shank having a recess in its front side extending upward from its lower end and a socket therein extending upward from the bottom of said recess, a thread guide post 95 mounted in said socket and extending into engagement with the bottom of said chamber in position to cause the thread to be drawn against the same and bent sharply as it is drawn to the shuttle eye, and a tension 100 felt inserted in said recess about the post and clamped between the same and the sides and bottom of the recess and the bottom of the thread block chamber, said felt being arranged to project beyond the sides of the shank into positions in which the thread 105 will be drawn thereagainst at both sides of the post as it is drawn against the post.

In testimony whereof, I have signed my name to this specification.

HENRY L. BONNEY.
